Conway L. Atwater, Georgetown, Conn.
Application June 15, 1946, Serial No. 676,937

9 Claims. (Cl. 135—19.5)

1

This invention relates to an umbrella. One of the objects of this invention is to provide an umbrella which is simple, thoroughly practical, and durable in use. Another object is to provide a device of the above character which may be manufactured from inexpensive materials with a minimum of labor costs. Another object is to provide a device of the above character which may be folded into a relatively small, flat package. Another object is to provide a device of the above character which may be assembled for use with extreme ease. Another object is to provide a device of the above character which may be opened in a minimum of time. Another object is to provide a device of the above character which will be neat and attractive in appearance. A further object is to provide a device of the above character in which the structural elements are so disposed as to attain a high degree of strength without heavy construction. Other objects will be in part obvious and in part pointed out hereinafter.

The invention accordingly consists in the features of construction, combinations of elements, and arrangements of parts, all as will be illustratively described herein, and the scope of the application which will be indicated in the following claims.

Referring now to the drawings in which is shown one of the various possible embodiments of this invention,

Figure 1 is a perspective view of the umbrella partially unfolded;

Figure 2 is a bottom plan view of the umbrella shown in Figure 1 assembled but before the connection of the handle thereto;

Figure 3 is a side elevation of the umbrella on an enlarged scale, certain parts being broken away for purposes of illustration;

Figure 4 is a vertical section on an enlarged scale taken on the line 4—4 of Figure 2;

Figure 5 is a vertical section taken on the line 5—5 of Figure 4, and

Figure 6 is a vertical section on an enlarged scale taken on the line 6—6 of Figure 2.

Similar reference characters refer to similar parts throughout the several views of the drawing.

As conducive to a clearer understanding of certain features of this invention, it might here be pointed out that people in cities and elsewhere are often caught in rain storms without umbrellas. At such time, it is extremely difficult to move from one place to another because transportation is not available, or if available,

2

is in use. Because of this, it is very often necessary for a person to walk a considerable distance in the rain which may result in costly damage to their clothing and may also affect their health. It is accordingly another object of this invention to provide an umbrella which may be readily carried in stock by newsstands and small stores and which will sell at a low price so that it will be available at all times to persons caught in rainy weather and can be thrown away by them after it has served its purpose.

In general, the umbrella consists of a framework, generally indicated at 9 (Figure 2) having a covering 20 made of waterproof paper or similar material. The framework includes a center section 10 which has a support 11 to which the handle 12 of the umbrella is detachably connected. The framework also includes four rib members, 13, 14, 15, and 16 which are hingedly connected to section 10 to permit them to be folded with the outside portions of cover 20 over section 10 to make a relatively small, flat package, as shown in Figure 1.

Section 10 of framework 9 is made of relatively rigid cardboard and has four wing portions 10a, 10b, 10c, and 10d formed on its four sides by notching the edges of section 10, as shown in Figure 2. The outer edges of each of the wing portions are aligned with each of the edges of section 10. Rib members 13, 14, 15, and 16 of the framework are made of cardboard of the same thickness as section 10 and are of the same width as wing portions 10a, 10b, 10c, and 10d, so that the longitudinal edges of each rib member are aligned with the sides of the wing portion to which they are connected.

The hinges 17, 18, 19, and 21 which connect rib members 13, 14, 15, and 16 to wing portions 10a, 10b, 10c, and 10d are preferably made of cloth or similar material which is secured by a suitable adhesive to the undersurfaces of the opposed ends of each wing portion and its rib member. This permits the rib members to be folded inwardly over section 10 and also provides a hinge of minimum thickness. To render

hinges 17, 18, 19, and 21 ineffective in order to maintain rib members 13, 14, 15, and 16 in an extended position in substantially the same plane as section 10, four sleeves, generally indicated at 22, 23, 24, and 25, are provided. As each of these sleeves is similar in construction and operation, the description will be limited to the construction and operation of sleeve 22 (Figures 2, 4, and 5).

Sleeve 22 may be made from relatively rigid

cardboard or sheet metal and includes a top 22a, a bottom 22b, and parallel side walls 22c and 22d (Figures 4 and 5). The top and bottom are spaced from each other a distance slightly greater than the thickness of rib member 13 taken together with hinge 17, and the distance between side walls 22c and 22d is slightly greater than the width of rib member 13. Thus sleeve 22 when mounted on rib member 13 may be slid longitudinally of rib member 13 and wing portion 10a (Figure 2) of section 10 so that it may either be positioned entirely upon the rib member 13 in the position sleeve 24 occupies in Figure 2, or when rib member 13 is in the same plane as section 10, it may be slid inwardly until its side walls strike the inner ends of the notches 10e and 10f in section 10. When sleeve 22 is in this position, as shown in Figure 2, it covers hinge 17 rendering it inoperative and rigidly holds rib member 13 in an extended cover supporting position.

Thus, when it is desired to condition the framework for use, the rib members are moved outwardly until they lie in the same plane as section 10, and then the sleeves 22, 23, 24, and 25 are slid inwardly until they cover the wing portions of section 10. At this time the sleeves render the hinges ineffective and rigidly connect the rib members 13, 14, 15, and 16 to wing portions 10a, 10b, 10c, and 10d. When it is desired to fold the framework, the sleeves 22, 23, 24, and 25 are slid outwardly until they are positioned entirely on the rib members. At this time the hinges are free to operate and the rib members may be folded over the section 10.

The cover 20 is preferably made from a circular sheet of waterproof paper. Section 10 of framework 9 is positioned in its center and is affixed to cover 20 by a suitable adhesive. The edge of cover 20 is folded inwardly on chords which are the same length as the width of section 10 and each of which is parallel to one of the edges of section 10. The chords on which cover portions 20a, 20b, 20c, and 20d are folded are also positioned outwardly from the outer ends of rib members 13, 14, 15, and 16 to permit relative movement between the rib members and cover 20 for purposes to be more fully disclosed herein-after. Each of cover portions 20a, 20b, 20c, and 20d is preferably stapled together by staples 35 on opposite sides of rib members 13, 14, 15, and 16 to form pockets similar to pocket 30 (Figure 4) in which the outer ends of the rib members are positioned.

Cover 20 is preferably folded on lines aligned with the edges of section 10, the two portions positioned outwardly from lines 31 and 32 (Figure 2) being folded inwardly first and then the other two portions 33 and 34 (Figure 1) are folded on top of the first-mentioned portions. When the folding portions of cover 20 are folded inwardly, the outer end of each of rib members 13, 14, 15, and 16 moves outwardly toward the outer end of the pocket in which it is positioned. This is permitted because of the depth of the pockets and is caused by the fact that the hinges are positioned on the underside of the rib members and the wing portions of section 10. Thus, the cover must fold over both section 10 and the rib members, and the distance each rib member moves outwardly is determined by the length of these folds.

The support 11 for handle 12 is preferably made of wood or similar material and is secured to the center of section 10 by a suitable adhesive. It has a hole 36 therein (Figures 2 and 6), the di-

ameter of which is slightly smaller than the diameter of handle 12. Thus, to connect handle 12 to support 11, one of its ends is forced into hole 36 and a secure connection is formed because of the resiliency of the wood from which handle 12 and support 11 are formed. When the umbrella is folded, handle 12 is positioned in a groove 37 cut diagonally across support 11, thus permitting a handle of maximum length to be kept in the folded umbrella without substantially increasing the thickness of the package the umbrella forms when folded.

Thus, an umbrella has been disclosed which may be folded into a compact and neat package of a type which may be readily stocked in any newsstand or small store. When it is desired to use the umbrella, the user simply unfolds the four folding portions of the cover, slides sleeves 22, 23, 24, and 25 inwardly and places one end of handle 12 in hole 36. The umbrella is then ready for use. If it is desirable to take down the umbrella in a cab, subway, or building, by simply sliding the sleeves 22, 23, 24, and 25 outwardly and replacing the handle 12 in groove 37, the user may refold the umbrella into a package that may be readily carried. It will be noted that the cover 20 is so constructed that it completely covers the framework of the umbrella and thus protects both the user and the umbrella itself from the rain.

It will thus be seen that a practical and efficient umbrella has been disclosed in which the several objects hereinabove mentioned, as well as many others, are successfully accomplished.

As many possible embodiments may be made of the above invention and as many changes might be made in the embodiments above set forth, it is to be understood that all matter hereinbefore set forth or shown in the accompanying drawing is to be interpreted as illustrative and not in a limiting sense.

What is claimed is:

1. In a device of the type described, in combination, a cover, a framework, said framework including a substantially flat relatively rigid center section and four, wide, flat rib members connected to the edges of said center section, the width of said center section being at least half the width of said cover, said cover being foldable over said center section along the edges thereof to form a substantially square flat package, means connecting said ribs to said cover, means connecting said cover to said square center section, means to support said rib members in cover supporting position, and a handle detachably connected to said center section.

2. In a device of the type described, in combination, a cover, a framework, said framework including a substantially square, flat, relatively rigid center section and a plurality of rib members, said center section being greater in width than the length of said rib members, said cover being connected to said center section, said rib members being hingedly connected to said center section, the hinged connections between said rib members and said center section being aligned with the edges of said center section, manually adjustable means to hold said rib members in cover supporting position, said cover and rib members being foldable over the center section of said framework to form a flat package, and a handle detachably connected to said center section.

3. In a device of the type described, in combination, a cover, a framework, said framework

including a substantially flat relatively rigid center section and a plurality of rib members, said cover being connected to said flat center section, said rib members being hingedly connected to said center section, means forming pockets at the outer edges of said cover, the outer ends of said rib members being positioned in said pockets, a plurality of members slidably mounted on said rib members, said slidably mounted members being manually adjustable to block the action of the rib member hinges and hold the rib members in an extended position, and a handle detachably connected to said center section.

4. In a device of the type described, in combination, a cover made of waterproof paper, a framework, said framework including a substantially flat relatively rigid center section made of cardboard and a plurality of cardboard rib members, said rib members being hingedly connected to said center section, means to support said rib members in an extended position, said cover and rib members being foldable over the center section of said framework, and a handle detachably connected to said center section.

5. In a device of the type described, in combination, a substantially circular cover made of waterproof paper, a framework, said framework including a substantially flat relatively rigid square center section made of cardboard and a plurality of rib members hingedly connected to said center section and also made of cardboard, said cover including portions folded inwardly to cover the outer ends of said rib members to form pockets within which the outer ends of said rib members are positioned, means to hold said rib members in extended position by blocking the action of said hinges, and a handle detachably connected to said center section.

6. In a device of the type described, in combination, a cover, a framework, said framework including a substantially flat, relatively rigid, square center section and four rib members, each rib member being substantially flat, of substantial breadth, and being hingedly connected to an edge of said center section, means forming pockets at the outer edge of said cover member in alignment with the outer ends of said rib members, the outer ends of said rib members being positioned in said pockets, means for blocking the action of each hinge to hold the rib members in cover supporting position, and a handle detachably connected to said center section, said cover and rib members being foldable inwardly along the edges of said flat center section to form a substantially flat square package.

7. In a device of the type described, in combination, a cover, a framework, said framework including a substantially flat, relatively rigid,

substantially square center section of a width approximately one-half the width of said cover and a plurality of rib members, said cover being connected to said center section and foldable thereover along the edges of said center section to form a substantially flat package, means connecting said rib members to said center section, said rib members being adjustable to support said cover when said cover is in an unfolded position, means to support said rib members in cover supporting position, means slidably connecting said rib members to said cover, and a handle detachably connected to said center section.

8. In a device of the type described, in combination, a cover substantially circular in shape, a framework, said framework including a flat, square, relatively rigid center section, the diameter of which is at least half the diameter of said cover when said cover is in open position and four rib members hingedly connected to the centers of the four sides of said center section, said rib members lying in substantially the same plane as said center section when in an open position and being foldable over said center section with said cover to form a substantially flat package, means to support said rib members in cover supporting position, a handle, and means detachably mounting said handle on said center section.

9. In a device of the type described, in combination, a cover substantially circular in shape, a framework, said framework including a flat, relatively rigid center section, a plurality of flat, relatively rigid rib members, said center section being of greater width than the length of said rib members, said rib members being mounted on said center section and being adjustable to support the outer portions of said cover, means connecting said cover to said center section, said rib members lying in substantially the same plane as said cover when in cover-supporting position and in a plane substantially parallel to said center section when in folded position, means to support said rib members in cover supporting position, and a handle detachably connected to said center section, said ribs and cover being foldable over said center section along its edges to form a flat package having a width slightly greater than the width of said center section.
